UNITED STATES PATENT OFFICE.

JAMES F. MAYS, OF BIRMINGHAM, ALABAMA, ASSIGNOR TO MAYS ACCOUNTING MACHINE COMPANY, OF LEXINGTON, NORTH CAROLINA, A CORPORATION OF NORTH CAROLINA.

CALCULATING-MACHINE.

1,309,535.

Specification of Letters Patent.

Patented July 8, 1919.

Application filed February 14, 1917. Serial No. 148,559.

To all whom it may concern:

Be it known that I, JAMES F. MAYS, a citizen of the United States, residing at Birmingham, in the county of Jefferson and State of Alabama, have invented certain new and useful Improvements in Calculating-Machines, of which the following is a specification.

My invention relates to a calculating machine for mechanically performing various computations.

One object of my invention is to design a calculating machine in which the keys, which drive the dials, may be simultaneously depressed in a number of columns or in all of the columns at the same time, both hands being available for this purpose, in order to expedite work while the carrying function of the machine is performed with perfect accuracy and reliability. To this end, it is the purpose of my invention to hold back or restrain the carrying mechanism of the calculating machine until the adding mechanism has completed its driving stroke on the dials and then, and not until then, to release the carrying mechanism, into which energy has been gradually stored, and permit it to advance, or move up one point, each of the several dials due to be carried into as a result of the previous advancement of the adding dials. By holding back the carrying mechanism I cause each individual unit of it to act at the same instant of time and I arrange for this action to occur when the driving or adding mechanism is at rest. My machine thus performs its adding function during the down stroke of the keys and its carrying function during the up stroke or interval of return or rest of the keys and therefore all of the numerals of a figure to be added may be struck simultaneously and the entire functioning of the machine controlled directly by the key action. This gives me the maximum speed of operation while at the same time safeguarding the perfect accuracy and reliability of the carrying function of the machine. Where the escapement mechanism controlling the carry is not held back but is allowed to operate freely while the adding is being done, an occasional "miss" will naturally occur in any operation when keys are struck simultaneously. Other methods of overcoming this fault, without holding back the carrying, have been devised but they involve a considerable complication of

parts and an increased expense of manufacture as compared with my solution of the problem which is of comparative simplicity and possesses a further additional value by reason of the fact that its special design is adapted for the incorporation therewith in a simple manner of an automatic stop for the carry overthrow of a means to lock the dial wheels when the mechanism is at rest.

My present invention, in fact, covers a compound carry mechanism, an overthrow stop, and a dial lock, and in respect of each of these characteristics it constitutes an important advance in the art of calculating machines, as trouble in respect of the same has been the chief cause of complex construction and inaccuracy of operation for such machines.

I employ as a preferred embodiment of my invention a rocker shaft transmission from the keys to the dial shafts and I provide a supplemental set of rocker shafts which control the mechanism for retarding the carry, locking the dials and stopping the overthrow.

The preferred mechanism for retarding the carry involves a compound or duplex escapement, one element of which is floating and drops in strict conformity to the movement of the carry mechanism, and the other element of which follows with a step advance when the up stroke of the keys unlocks it and this following escapement element locks the dials after permitting them the one step advance movement necessary to make the carry. The overthrow stops are arranged on the main and supplemental rocker shafts so that they normally interlock, the key action being adapted to unlock these parts before engaging the main rocker shafts to move the dials.

In my present invention I employ many of the features of construction and arrangement of parts embodied in my earlier patents, and particularly in Letters Patent No. 1,165,337, wherein is described the carry actuating mechanism which is employed in my present construction but instead of imparting the carrying movement directly to the dials as in the said Letters Patent, this movement is stored and imparted to the second element of the duplex escapement which is adapted to have the carrying movement suspended in it until the completion of the direct adding operation.

In obtaining for the keys a uniform depth of stroke I have provided for a direct operating connection to the rocker shafts only from the keys of higher denomination, the 5 other keys acting through a series of levers upon a common actuator for the rocker shaft, the lever connections being such as to impart the requisite differential movement to the actuator as a result of a light and uniform 10 form movement of the several keys in its respective column.

These and other advantages of my invention may be better understood by reference to the accompanying drawings, wherein I 15 have sought to illustrate only what I regard as the preferred embodiment of my invention, and in which:—

Figure 1 is a partial vertical section from front to rear of the machine showing one 20 column of keys in elevation and showing the dial operating mechanism controlled thereby partially in vertical cross section.

Fig. 2 is a detail view showing in front elevation both cam driven escapement elements of the carry mechanism.

Fig. 3 illustrates in rear elevation the lock pins in different operating positions for preventing the rebound of the dial rocker shafts.

Fig. 4 is a detail view, partly in section, showing the construction of the common rack key and the sector which it operates.

Fig. 5 is a detail view, partly in section, showing the construction of one of the 35 higher denomination keys and the sectors operated by it.

Fig. 6 is a detail view of the bearing bracket for the mechanism for shifting the oscillatory bar.

Fig. 7 is a plan view with the keys removed and also omitting the transmission details of the carrying mechanism by showing their respective staggered arrangement.

Fig. 8 is an enlarged cross sectional view 45 of the floating escapement wheel of the carry mechanism as taken on the line 8—8 of Fig. 7.

Fig. 9 shows in three diagrammatic views the relative movements of the floating escapement wheel and the spring carrying gear pins.

Fig. 10 is a plan view of one of the double detent mechanisms which control the release of the spring element in which the carry is stored.

Similar reference numerals refer to similar parts throughout the drawings.

The apparatus illustrated in the drawings as the preferred embodiment of my present 60 invention, comprises a machine casing having a top 1, a back plate 2, an intermediate transverse vertical plate or partition 3 interposed between the banks of keys 4 on one side and the operating mechanism for the 65 dials 5 on the other side, which dials are

mounted upon shafts 6 journaled at their inner ends on a bearing bar 7 attached to the partition 3, and at their outer ends in a cross bar 8 made fast to the front end of the machine (not shown). Below the banks of 70 keys is arranged a bottom guide plate 9 made fast to the plates 2 and 3 and provided with holes to receive and form a bottom guide for the lower ends of the key stems which at the end of their down stroke 75 engage the base plate 10 of the machine. These key stems are made of flattened metal strips having their lower portions within the casing twisted at right angles and provided with rack teeth 11, as seen in Figs. 4 and 5. 80 These teeth 11 on each key are adapted to mesh with the teeth 12 of its respective toothed sector 13, one of which is made fast on each rocker shaft 14 opposite the "7", "8" and "9" keys of each column. The keys 85 of lower denomination than "7" in each column carry a lateral pin 15 which projects into an elongated slot 16 at the outer end of a lever 17, 17^a, 17^b, 17^c, 17^d, or 17^e, as the case may be, each of these levers projecting at 90 their rear ends through suitable slots in the back plate 2 and having a pivotal bearing on pins 18 in a back bracket 19 formed by pairs of angle plates which have lugs out-turned and made fast by screws 20 to the back 95 plate. The several keys from "1" to "6" inclusive, in each column, are severally connected to a corresponding lever 17, 17^a, etc., and these several levers for each column of keys are arranged in two banks of three 100 each, one bank being arranged to pass on one side of the column of keys and of a common rack key 21 and the other bank on the opposite side thereof. This rack key 21 carries a stepped cross bar 22 with offset 105 shoulders of graduated height disposed to be engaged respectively by the levers 17, etc., and to be moved downwardly thereby for the predetermined distance, depending on the denomination of the key depressed. The 110 several levers have a variable stroke due to varying lengths and being pivoted at different distances from the common rack key 21 and this will bring the lower edges of the levers at different heights where they pass over the bar 22 for which reason it is desirable to shape the bar so that it will engage each lever. The operating connection 115 thus provided between the key 21 and the levers can be made in other ways but that shown is ample to illustrate my purposes. It is intended that each key 4 shall have exactly the same length of down stroke but it will be obvious that the angular movement of its respective lever 17, 17^a, etc., will depend upon the length of the lever and the distance of its pivot from the common rack key. In this manner I obtain very simply 120 and effectively the differential dial driving movement from a uniform key movement. 130

I prefer to interpose the levers, as the operating connection between the first six keys of lower denomination in each column, as it would be difficult to work out a plan for 5 the uniform key stroke with a direct connection without interposition of some equivalent means and I consider this form shown the simplest for my purposes. Each common rack key 21 carries teeth 11 which mesh 10 with teeth 12 on its respective sector 13 on shaft 14 and serve to rotate the latter in the same manner as the teeth 11 on the key stems for the "7", "8", and "9" keys.

As illustrated in Fig. 1, I employ coil 15 springs 23 which are fastened to the top plate 1 and one of which is connected to each key stem to effect its return after being depressed. For sake of clearness, in Fig. 1 I have omitted all but one of such 20 springs. The lower end of either rack bar 21 carries a spring seat 24 which bears against a coil spring 25 surrounding its stem and interposed between the seat 24 and the bottom 9, thus providing for the return 25 of the common rack keys. The upper end of these rack keys are received in angled guide plates 26 which are secured to the top plate 1 and extend down into position to engage the upper end of each rack bar so 30 as to guide it in all of its operating positions. Each of the key stems is provided with a supplemental set of teeth 27 below and spaced from the teeth 11, and these teeth on each key are adapted to mesh with 35 teeth 28 on a respective sector 29 made fast on a bottom rocker shaft 30 journaled in the plates 2 and 3. As a means for bringing the sectors 13 and 29 into toothed engagement with their respective key stems, I 40 provide pins 31 and 32 on each key stem and I provide each sector with an arm 33, it being noted in Fig. 5 that the arm 33 of sector 29 stands in engagement with the pin 32, whereas the arm of the sector 13 is in 45 the path of, but is spaced substantially from its respective pin 31. The object of this is to cause each key stem as depressed to engage and impart a rocking movement to its respective lower rocker shaft 30 in ad- 50 vance of engaging and rocking its respective rocker shaft 14 through which it drives its receptive dial. In other words, I provide what may be termed a lost-motion driving connection between the key 55 stems and the dial operating rocker shafts 14 and with a positive driving connection to the lower or supplemental rocker shafts 30. The purpose of this will be understood by reference to Fig. 3, where it is seen that 60 each corresponding pair of rocker shafts 14 and 30 carry fast thereon co-acting lock pins 34 and 35 which are so disposed relatively that when a pair of shafts 14 and 30 are in initial position the lock pin 35 65 will engage under and set at right angles

to the lock pin 34 (see the pins on the left hand shafts, Fig. 3). This position of the lock pins positively locks the dial operating shafts 14 against movement and the preliminary movement imparted by pin 32, 70 arm 33 and sector 29 to the rocker shaft 30, will rock the pin 35 to its upper dotted position, clearing the pin 34 in advance of the engagement of the key with the sector 13. After the pins are thus un- 75 locked, both shafts are free to take the full movement imparted to them by the key depressed and on the return the pins will automatically resume their locked position, thus holding the dial operating shafts 14 80 locked at all times except after the keys have been substantially depressed and prevent a rebound of the drive mechanism which imparts motion from the shafts 14 to the dials. 85

The dial driving mechanism comprises a toothed sector 36 made fast on the forward end of each shaft 14 beyond the plate 3 and meshing with a pinion 37 which turns freely on shaft 6 and through a ratchet 90 drive imparts a counter-clockwise movement, as viewed from the front, to the ratchet wheel 38 fast on the shaft 6. The pinion 37 is returned to initial position with the sector 36 responsive to the action 95 of a coil spring 39 on the shaft 14 and it is to prevent a rebound from this return movement that the lock pins are provided. The counter-clockwise movement imparted to the shaft 6 will advance the dial 5 proportionately with the value of the key depressed and in like manner the compound gear 40 is rotated, its teeth 41 meshing with a train of gears partially indicated by 42 which serve to wind and increase the tension of the spring of the carry mechanism of the dial of next higher denomination, all as more fully and exactly described in my Letters Patent No. 1,165,337. The other teeth 43 of the gear 40 mesh with a pinion 110 44 which drives a sleeve 45 upon which is mounted two cams 46 and 47. The sleeve and gear turn on a shaft 48 mounted on a cross bearing bar 49 made fast to the sides of the machine, and the cams, as seen in 115 Fig. 2, are reversely set and are adapted to move in reverse direction, bell crank levers 50 and 50^a which at their free ends carry pallets 51, these pallets having a limited play therein responsive each to a 120 spring 52, all as more fully described in my said Letters Patent. The bell cranks are held in engagement with the cams by springs 53 and each pair is mounted on a common bearing pin 54 secured in a bottom extension of the bearing bar 49. The pallets, as thus reversely moved, co-act with an escapement action, on the ten teeth 55 of the floating escapement wheel 56 which forms the floating element of the escape- 125 130

ment. In Fig. 8 the operation of the pallets is more clearly shown and their function is to permit this floating wheel 56 to drop as soon as the cams reverse the position of the pallets 51, thereby releasing the floating wheel for a one step advance. This advance is caused by the action of a coil spring 57 which is connected at one end to a pin 58 on the floating wheel 56 and at 10 the other end to a pin 59 carried by the gear 60 forming part of the follow element of the escapement. Each escapement mechanism comprises a pinion 61 which meshes with the gearing that transmits the carrying motion from the dial shaft of next 15 lower denomination, this gear 61 is turned one tenth of a revolution as the adjacent shaft of lower denomination makes a complete turn. This gear 61 carries a pin 62 20 which projects through a slot 63 in the floating wheel 56 and has fast to it, and disposed between it and wheel 56, a main power spring 64 which is passed about the shaft 6 in a reverse direction to that of the 25 spring 57 and is made fast to the pin 59 on the gear 60. This pin 59 also projects through a slot 65 in the wheel 56 of the same length as and diametrically opposite to the slot 63, the length of these slots being just sufficient to permit a one step or 30 36° advance of the floating wheel 56 when it is released by its pallets 51 to respond to the action of the spring 57. The gear 60 is provided with ten teeth and carries a 35 pawl 66 (Fig. 1), which co-acts with ratchet teeth 67 on a gear 68 which is provided with ten teeth and made fast to the dial shaft 6. The gears 60 and 61 are mounted upon a sleeve 69 made fast in a cross bearing bar 40 70 which has depending bearing extensions 71 for the trains of carrying gears 42. These sleeves 69 carry at one end a deep cut collar which fits in a seat in the bearing bar 70 and is held in place by top bars 45 72, and at its other end it has an upturned shoulder to hold the gear 60 in position. The bore through this sleeve is substantially greater than the dial shaft 6 which therefore turns free of contact therewith. The 50 gear 60 has a hub flange inturned and butting against a thicker hub flange for the gear 61 and on this hub flange of the gear 60 I mount the floating wheel 56 which is held in position by its hub flange that runs 55 between the wheel 60 and the hub flange of the wheel 61. This gives a close assembly of the several wheels of the compound carrying mechanism. The teeth on the gears 60 and 68 are set opposite each other and 60 are adapted to be alternately engaged by a locking escapement pawl which is shown in side elevation in Fig. 2 and in plan in Fig. 10. This pawl comprises an upturned rocker arm 73 which engages a pawl rock- 65 ing mechanism hereinafter described. At

its lower end this arm is bent to one side where it joins to a pawl which rocks on a vertically disposed center bearing 74 which is provided with a rigid detent 75, projecting to the right of its bearing and disposed 70 in position to engage the teeth of the gear 60, and with an extension 76 projecting to the left of its bearing and having pivoted to its outer end a spring pressed detent 77 which is normally held forward against a 75 stop pin 78 on the pawl by means of a coil spring 79 connecting the detent 77 and the pawl. The pawl has a further extension to the left which is bent over at its outer end 80 to form a limit stop for the yielding 80 movements of the detent 77. As seen in Fig. 2, the detent 77 in dotted lines is shown in its normal position relative to the pawl when not yielding to permit a carrying operation. The moment the pawl is 85 rocked to disengage the detent 75 from the gear 60, the latter is free to be moved by the tension of the spring 64 exerted on its pin 59 and will drop the length of slot 65, which is equal to a one step advance. In 90 taking this movement, by means of the pawl and ratchet connection 66, 67, the gear 68 will be driven with it but this movement of the gears 60 and 68 will be opposed by the yielding detent 77, which 95 will, however, permit the gears to move until the detent 77 strikes its limit stop 80, which occurs after the gears have made one complete advance step and it thereupon locks the gears 60 and 68 and the dial 100 against further movement until the pawl is reversely rocked to cause the rigid detent 75 to move into position to lock the gear 60 when the detent 77 drops out of engagement with the gear 68 and is then drawn by its 105 spring 79 to its dotted line position ready for the same operation to be repeated. The yielding detent 77 when snapped forward to its dotted line position, will bring its point into position to engage the next tooth 110 on gear 68 when again rocked into operative position. The necessity for the ratchet connection between the gears 60 and 68 arises from the fact that the gear 68 revolves with the dial shaft 6 under the key stroke, 115 whereas the gear 60 responds only to the carrying operation. When the pawl is rocked to bring the rigid detent 75 into position to lock the gear 60, the same movement brings the yielding detent 77 into position to clear the teeth of the gear 68 and the latter is therefore free to revolve with the dial shaft during the adding operation. The moment the adding operation is completed the yielding detent is shifted into its 120 dotted line position, Fig. 2, and the rigid detent 75 is withdrawn to clear the gear 60 and the gears are then ready to perform the carrying function if such is due.

The mechanism for controlling the move- 125

ments of the escapement locking pawl comprises cams 81 which are made fast on the forward ends of the rocker shafts 30 and are shaped as shown in Fig. 2, where it will be seen that they comprise a cam face 82 which merges into a bearing face 83 concentric with the shafts 30. The cam faces 82, in the normal position to which the shafts 30 are retracted by coil springs 84, bring them in position to engage the rollers 85 which are rotatably mounted upon bearing pins 86 made fast to a common rocker shaft 87, which rocker shaft extends transverse across the machine under the bank of shafts 30 and is mounted in bearings 88 attached to the side plates. A coil spring 89 serves to return the shaft 87 to its normal position. An arm 90, made fast to the left hand end of shaft 87, has connected to its outer end a pull bar 91 which extends upwardly and is connected to one end of a bell crank lever 92 which carries at its other end a curved toothed segment 93 and which is mounted to turn with a shaft 94 journaled in a bearing bracket 95 (Figs. 6 and 7). This bracket is connected to the side wall of the machine. The toothed segment 93 meshes with a gear 96 mounted above it on a pin 97 which turns in the bracket 95. The gear 96 carries a crank pin 98 to which is connected a pull bar 99 pivotally connected at its other end to a bracket 100. This bracket 100 is connected to a reciprocatory bar 101 that is mounted upon the several vertical arms 73 of the locking escapement pawl, these arms being disposed alternately on opposite sides thereof. The bar 101 is provided with laterally projecting pins 102 which rest in open notches 103 at the top of the arms 73 and is thus supported on these rocking arms above the bearing bar 49 and free of frictional engagement therewith. The pin 98 is so positioned relatively to the center of the gear 96 that in its initial position it stands on one side thereof and when the cams 81 rock the segment 93 the gear 96 is caused to move through an arc of approximately 180°, which brings the pin substantially on a dead center on the other side of the shaft 97. The advantage of this is that any pull exerted by reason of the action of the spring pressed gears 60 and 68 on the locking escapement pawls, will be transmitted through the connections described to the bearing shafts 97 and will not be reflected as a pressure to be overcome on the operation of the keys 4 of the machine. In other words, the spring load on the reciprocatory bar is taken entirely by the bearing pin 97 and is thus kept off of the keys. This is an important arrangement for the purpose of preserving a light, free key action of the machine.

In order to limit the up stroke of the several keys 4, the latter are provided with pins 104 which strike the under side of the

top of the casing. The keys are provided with the ordinary type of buttons 105.

In operation, upon the depression of a key, for instance the "5" key in the column of keys shown in Fig. 1, the following operations take place in the order of their recital. The lever 17^a is depressed, carrying with it the common rack key 21. The teeth 27 at the bottom of the key 4 engage the sector 29 on shaft 30 and rocks its lock pin 35 out of locking position with the pin 34 on the shaft 14, thus freeing the latter. Before the shaft 14 is rotated the shaft 30 turns and by the action of its cam 82 on the roller 85, depresses the rocker shaft 87, pulls down on the arm 90, and through the pull bar 91, bell crank 92 and gears 93 and 96, the reciprocatory bar 101 is drawn to the left, Fig. 2, rocking with it the several locking escapement detents 75, 77 to lock the gears 60 and 68. Thereupon the teeth 11 on the rack 21 engage sector 13 and begin to rotate shaft 14, which through the gears 36, 37 and the ratchet 38, will drive shaft 6 and with it the dial and gear 68 through five steps. At the same time the gears 43 and 44 will be driving the cams 46 and 47 and winding, through the gears 42, the gear 61 of the carrying mechanism for the dial of next higher denomination. The moment the key is released it is snapped to initial position by its spring 23, the common rack key is returned by its spring 25. The shafts 14 and 30 are returned by their respective springs 39 and 84 and the pins 34 and 35 immediately resume locked position. The gear 37 returns with the reverse movement of the gears 36 which is permitted by its ratchet connection 38 and thus the machine is ready for another operation. As the shaft 30 resumes initial position, the shaft 87 was free to be moved upwardly by its spring 89, which would move arm 90 and result, through the operating connections described, in reversing the position of the reciprocatory bar 101, thereby throwing out the rigid detents 75 which lock the gears 60 and set the spring detents 77 in position to catch and arrest the gears 60 and 68 in moving one step. If there is no carry to take effect into the carry mechanism shown, the gears 60 and 68 are held by the engagement of pin 59 with the floating wheel 56 (see Fig. 8) and remain in the position in which they were left, being also locked against rotation by the yielding detent 77, but if the dial shown is due to be carried into, the cams 46 and 47 will have so positioned their respective bell crank pallet levers that the floating wheel 56 will have been permitted to drop forward one step by the escapement pallets 51. This operation was performed on the down stroke of the key while the carrying gear 60 was held by the rigid detent 75 until the down stroke was complete.

On completion of the down stroke and as the key returns upward, the rigid detent 75 releases the gear 60 which drops forward one step to follow up the floating wheel 56 and carries with it the gear 68, moving it against the resistance of the yielding detent 77, and thus turns the dial one step, making the carry. The train of gears 41 and 42 impart a movement of gear 61 on shaft 6 of next higher denomination of exactly one tenth of that made by the dial shaft holding the driving gear. This is for the purpose of keeping the rotating spring 64 in tension. Upon the release of the key the bar 101 shifts to the right to reverse the positions as above described of detents 75 and 77.

In Fig. 9 I have attempted diagrammatically to show the step by step follow up action of the two elements of the escapement, it being borne in mind that the upper pin 62 is rigid on the gear 61 which forms part of the driving portion of the carry mechanism, whereas the pin 59 is fast on the gear 60 forming part of the driven portion of the carry mechanism due to be restrained. In the left hand figure the pin 62 has been advanced a full carrying travel to the right in slot 63. In the middle figure the cams 46 and 47 have acted on the pallets 51 to release the floating escapement wheel 56 and it has snapped forward responsive to the tension of the small spring 57 and will be held in this position by the pallets. The moment the gear 60 is unlocked the main spring 35 will act to snap it to the left and shift its pin 59 into engagement with the left hand end of slot 65, see final position, and in making this movement the gear 60 carries with it the gear 68 and the dial. The pin 62 is left at the left hand end of its slot 63 and therefore free to advance responsive to the drive from gears 41, 42 and 61.

Having thus described my invention, what I claim as new and desire to secure by Letters Patent, is:—

1. In a calculating machine, dials, dial operating mechanism, and a compound carrying mechanism coöperating therewith and comprising a floating holding member movable directly responsive to the operation of the dial carried from and acting to partially effect the carry, an escapement follower for completing the carry, and key controlled means to restrain the operation of said follower until the said holding member has completed its travel.

2. In a calculating machine, dials, dial operating mechanisms, and compound carrying mechanism coöperating therewith and comprising each a driving portion having a stop or holding member adapted to advance directly responsive to the movement of the dial operating mechanism being carried from and acting to partially effect the carry, a driven portion comprising a member

adapted to follow step by step the movement of said holding member, mechanism to complete the carry to the dial to be carried into, and ratchet mechanism for driving said dials, and key controlled means to restrain the operation of said follower until said holding member has completed its travel.

3. In a calculating machine, dials, keys, mechanism driven by the keys for moving the dials, carrying mechanisms comprising each a yieldable actuating element, and means controlled in common by any of the keys and common to a plurality of carrying mechanisms to restrain the actuating element of each carrying mechanism and thus delay the carry during the key driven motion of the dials.

4. In a calculating machine, dials, keys, mechanism driven by the keys for moving the dials, carrying mechanisms comprising each a spring actuating element, and means controlled in common by any one of the keys and common to a plurality of carrying mechanisms to restrain the spring actuating element and retard the carry during the key driven motion of the dials.

5. In a calculating machine, dials, columns of keys, key driven mechanism for moving the dials, carrying mechanisms comprising each a yieldable spring element, means common to a plurality of columns of keys and to a plurality of carrying mechanisms and responsive to the down stroke of the keys to restrain the yieldable element from imparting the carry to the dial to be carried into, said yieldable element being released by the up stroke of the actuated keys to complete the carrying operation, substantially as described.

6. In a calculating machine, dials, columns of keys, key operated dial actuating mechanisms, carrying mechanisms for the dials, each of which includes a spring-pressed yieldable element, means movable responsive to the driving stroke of a key of any of said columns to engage and restrain the yieldable element of all the carrying mechanisms until the driving stroke is completed, said yieldable elements when released being adapted to spring forward and complete the carry operation.

7. In a calculating machine, dials, columns of keys, key operated dial actuating mechanisms, carrying mechanisms for the dials, each of which includes a spring element on which the direct carry movement is stored, means movable responsive to the driving stroke of a key of any column to engage and restrain the spring element of all the carrying mechanisms until the driving stroke of all the actuated keys is completed, said spring elements when released being adapted to spring forward and complete the carry operation.

8. In a calculating machine wherein the

dials are directly driven by the keys, columns of keys, key actuating mechanisms, carrying mechanisms, each of which includes a spring-pressed yieldable transmission element, and a ratchet mechanism driven by said spring-pressed element when released to complete the carry, and a common restraining mechanism for said several yieldable elements operative responsive to the direct dial driven action of a key of any column and comprising means to restrain said yieldable elements throughout the dial driven actions of the keys.

9. In a calculating machine, dial operating mechanisms, compound carrying mechanisms co-acting with said dial operating mechanisms and each comprising a driving element and a floating stop element capable of advancing in response to the movement of the dial operating mechanism being carried from, a ratchet mechanism, and a spring connection to transmit motion from said driving element through the ratchet mechanism to the dial operating mechanism being carried into, and key controlled means co-operative with said floating stop element to predetermine the extent and limit the advance of said ratchet mechanism, substantially as described.

10. In a calculating machine, a carrying mechanism including an element rotated responsive to the movement of the dial of lower order, a spring-pressed floating escapement wheel, escapement mechanism controlled by the dial of lower order and acting to permit said wheel to advance step by step, ratchet wheels, means rigidly connecting one of the ratchet wheels to its respective dial, spring means connecting the other ratchet wheel to said first mentioned element, a key controlled compound rocking detent comprising a rigid stop adapted to act on the spring-pressed ratchet wheel, and a yieldable stop adapted to act on the other ratchet wheel and to yield sufficiently to permit both ratchet wheels to advance one step with its yielding motion, said stops being positioned to alternately engage their respective ratchet wheels, and means engaging the floating wheel and limiting to a unit carrying movement the spring-pressed ratchet wheel when released by its stop.

11. In a calculating machine, dials, key actuating mechanism to operate said dials, an oscillatory bar movable responsive to the key action of the machine, carrying mechanisms including each a yieldable intermediate spring tensioned element, mechanisms movable by said bar to lock and unlock said yieldable elements, and means to limit the stroke of the yieldable elements when unlocked to that of a single carrying movement, substantially as described.

12. In a calculating machine, keys, an oscillatory bar movable responsive to the key

action of the machine, carrying mechanism each including an escapement mechanism which comprises a yieldable intermediate spring tensioned element, mechanisms movable by said bar to lock and unlock said yieldable elements, means to limit the stroke of the yieldable elements when unlocked to that of a single carrying movement and the key operated driving connections for said bar comprising a crank, and a rotatable element to which the crank is connected and which is adapted to advance the crank connection to substantially a dead center position when the bar is moved by the depression of a key into position to restrain the carrying movement of said yieldable elements.

13. In a calculating machine, key actuated dial operating mechanisms, key controlled mechanism to lock the dials against movement except during the driving action of said dial operating mechanisms, carrying mechanisms, means common to all the carrying mechanisms and controlled by any one of said dial operating mechanisms to restrain the functioning of the carry mechanisms during the driving action of the dial operating mechanism, and means in said dial locking mechanisms to yieldingly permit a one step advance of the dials in response to the carrying mechanisms of the dials to be carried into.

14. In a calculating machine, keys, dials, dial actuators operable by said keys, carry mechanisms comprising a spring-pressed yieldable element, supplemental actuators adapted to be driven by the keys in advance of the dial operating actuators, mechanism common to all the carry mechanism controlled by the supplemental actuators to co-operate with said yieldable elements of the carry mechanisms and restrain the performance of the carrying functions until the completion of the key driven movement of the dials, and co-acting elements on the actuators controlled by each key which are disposed to assume position to lock the main actuator against rebound at the conclusion of the up stroke of the keys.

15. In a calculating machine, keys, two rocker shafts actuated by each key, one being started in advance of the other, pins on said rocker shafts adapted to interlock when the shafts return to initial position and thus prevent a rebound movement of the dial operating shaft, a dial operating mechanism driven by one shaft, and a carrying mechanism and a key restraining mechanism therefor actuated by the other shaft.

16. A calculating machine comprising a dial, mechanism actuated directly by the down stroke of a key for operating said dial, carrying mechanism comprising means responsive to the down stroke of such key to partially effect the carrying operation, and

means responsive to the initial part of the down stroke of such key to restrain the carrying mechanism and thus prevent completion of the carrying operation and also responsive to the up stroke of such key to release the carrying mechanism and thus complete the carrying operation.

17. In a calculating machine, dials, keys, actuating mechanism individual to each dial 10 for operating the dials from the respective columns of keys, carrying mechanisms for the respective dials, and mechanism operative by a key of any one of said columns and common to the several carrying mechanisms 15 to time the operations of said carrying mechanisms.

18. In a calculating machine, dials, keys, actuating mechanism individual to each dial for operating the dials from the respective 20 columns of keys, carrying mechanisms for the respective dials, and mechanism releasable by a key of any one of said columns and common to the several carrying mechanisms to simultaneously control the same.

19. In a calculating machine, dials, key 25 actuated dial operating mechanism, and a compound carrying mechanism, comprising an escapement wheel capable of advancing directly in response to the operation of the dial carried from and operating on the movement of a key in one direction to predetermine and limit the extent of advance of the carrying mechanism, a second escapement wheel, and means controlled by such 30 key to cause advance of said second wheel to the extent predetermined by said first mentioned escapement wheel after such key is permitted to move in another direction.

20. In a calculating machine, dials, key 40 actuating dial operating mechanism, and a compound carrying mechanism comprising an escapement wheel capable of advancing directly in response to the operation of the dial carried from and operating only on the 45 down stroke of a key to predetermine and limit the extent of advance of the carrying mechanism and a second escapement wheel controlled by such key and operating to advance to the extent determined by said first 50 named escapement wheel only after the down stroke of such key is completed, said second escapement wheel then acting to complete the carrying operation.

21. In a calculating machine, dials, key 55 actuated mechanism for operating said dials, mechanism for carrying from a dial of one denomination to a dial of another denomination, said carrying mechanism comprising a double escapement having a rotatable stop 60 member responsive to the action of a key corresponding to the dial to be carried from and acting on the movement of said key in a direction to impart travel to said dials, a follower associated with said 65 stop member and having its movement

limited thereby, mechanism to restrain the movement of said follower when a key is operated to rotate its corresponding dial and to release said follower to permit it to complete the carrying operation when the 70 key is allowed to travel in a direction opposite to that in which it moves to operate its corresponding dial.

22. The combination in a calculating machine, of a series of numeral dials, individual driving mechanism for each dial and adapted to be operated simultaneously, keys 75 for operating said driving mechanism, escapement mechanisms individual to the respective numeral dials and operable by said driving mechanisms to partly effect the carry, escapement control mechanism common to all of said escapement mechanism, and supplementary mechanism actuated by any one of said keys for operating said 80 escapement control mechanism.

23. The combination in a calculating machine, of a series of numeral dials, individual driving mechanism for each dial and adapted to be operated simultaneously, keys 90 for operating said driving mechanism, escapement mechanisms individual to the respective numeral dials and operable by said driving mechanisms to partly effect the carry, escapement control mechanism common to all of said escapement mechanism, and supplementary mechanism actuated by a key for any one of said dial driving mechanisms for operating said escapement control mechanism, said escapement control mechanism 95 permitting a carrying movement into a plurality of said dials simultaneously.

24. In a calculating machine, a series of numeral dials, a series of escapement mechanisms co-operatively associated therewith, and 105 each comprising a floating wheel and a driving wheel, and a series of driving wheel controlled detents adapted to act upon the entire series of driving wheels simultaneously and permit them to advance one step after 110 each adding operation.

25. In a calculating machine, a series of numeral dials, a series of floating wheels adapted to move step by step responsive to the action of the dial carried from, a series 115 of driving wheels adapted to move step by step responsive to the action of an escapement control mechanism comprising a series of detents each having a rigid stop, and a flexible stop, and each detent acting on both 120 a numeral dial and a driving wheel, and a reciprocatory bar on which all of said detents are mounted.

26. In a calculating machine, a series of numeral dials, a series of floating wheels 125 adapted to move step by step responsive to the action of the dial carried from, a series of driving wheels adapted to move step by step responsive to the action of an escapement control mechanism comprising a series 130

of detents each having a rigid stop, said rigid stop acting to control the driving wheel, and a flexible stop acting to control a dial, a movable supporting member common to all of said detents, and key operated means to actuate said supporting member.

27. In a calculating machine, a series of numeral dials, a series of non-driving floating escapement wheels, a series of driving wheels movable responsive to the action of the numeral dial carried from and adapted to be normally held by said floating wheel, a movable member common to said series of driving wheels, and a series of detents one individual to each of said driving wheels and responsive to the movement of said movable member to control said driving wheels.

28. In a calculating machine, a series of numeral dials, a series of escapement mechanisms, each having a floating wheel and a driving wheel, and an escapement control mechanism adapted to act upon the entire series of driving wheels simultaneously but non-operative upon said floating wheels.

29. In a calculating machine, a series of numeral dials, a series of key driven actuators for said dials, carrying mechanisms for said dials, each of which mechanisms includes a floating wheel and a driving wheel, means responsive to the downward stroke of any key to control the movement of the entire series of driving wheels simultaneously, until the downward stroke is completed, and then to permit the entire series of driving wheels to move forward one step, and an elastic stop individual to each driving wheel to limit said last-mentioned movement.

30. In a calculating machine having numeral dials directly driven by keys, numeral wheel operating mechanisms, double wheeled escapement mechanisms concentric with the numeral dials, each of which includes a floating wheel responsive to the movement of the numeral dial carried from, and a driving wheel, and key controlled means which, in co-operation with the floating wheel, is adapted to control the functioning of said driving wheel.

31. In a calculating machine having a plurality of key actuated numeral dials, a reciprocatory bar movable responsive to the key action of the machine but independent of the dial action, a series of escapements including each a spring-pressed floating element and a spring-pressed driving element, mechanisms movable by said bar to unlock or lock the entire series of driving elements simultaneously, and means to limit the travel of the driving elements to that of a single carrying movement.

32. In a calculating machine, columns of keys, a series of numeral dials, dial actuators operable by said keys, a series of escapement mechanisms each comprising a spring-

pressed element, supplemental actuators adapted to be driven by the keys in advance of the dial operating actuators, mechanism controlled by the supplemental actuator to unlock or lock the entire series of escapement mechanisms at the same instant of time, and co-acting elements on the actuators to lock the main actuator against rebound at the end of a stroke.

33. In a calculating machine having key actuated dials driven by the direct down stroke of the keys, a series of double wheeled escapements concentric each with one of said dials, each of said escapements comprising a floating wheel, and a spring driven driving wheel, the floating wheel moving forward one space for each dial to be carried into and operable by the down stroke of a key, the driving wheel corresponding to said floating wheel and subsequently moving forward one step to follow the floating wheel, said floating wheel having means to limit said movement of the follow wheel and hold it against the tension of its driving spring.

34. The combination with adding wheels relatively arranged for progressive registrations thereon, of carrying mechanisms comprising a floating escapement wheel and a driving escapement wheel rotatively connected with a higher denomination wheel, a low tension spring applied to the floating wheel, and a high tension spring applied to the driving wheel, and both springs tensioned by the lower denomination wheel.

35. The combination with adding wheels relatively arranged for progressive registrations thereon, of carrying mechanisms comprising a floating escapement wheel and a driving escapement wheel rotatively connected with a higher denomination wheel, a low tension spring applied to the floating wheel, a high tension spring applied to the driving wheel, both springs being tensioned by the lower denomination wheel, and a slot and pin connection between the two wheels, the slot being applied to the floating wheel and the pin to the driving wheel.

36. The combination with adding wheels relatively arranged for progressive registration thereon, of carrying mechanisms comprising a floating escapement wheel and a driving escapement wheel rotatively connected with a higher denomination wheel, a low tension spring applied to the floating wheel, a high tension spring applied to the driving wheel, both springs being tensioned by the lower denomination wheel, and a slot and pin connection between the two wheels, the slot being applied to the floating wheel and the pin to the driving wheel, and the slot being adapted to move forward one tenth of a revolution in advance of the pin, and the pin being adapted to follow the slot with a one tenth revolution.

37. The combination with adding wheels

- relatively arranged for progressive registrations thereon, of carrying mechanisms comprising a floating escapement wheel and a driving escapement wheel rotatively connected with a higher denomination wheel, a low tension spring applied to the floating wheel, a high tension spring applied to the driving wheel, both springs being tensioned by the lower denomination wheel, and a slot and pin connection between the two wheels, the slot being applied to the floating wheel and the pin to the driving wheel, and the slot being adapted to move forward one tenth of a revolution in advance of the pin, and the pin being adapted to follow the slot with a one tenth revolution, the two escapement wheels being interengaged for movement as one but the slot bearing wheel making its movement in advance of the pin bearing wheel.
38. In a calculator of the type wherein the dials are advanced on the down strokes of the keys, dials, dial operating mechanisms, floating wheel escapement mechanisms adapted to advance in response to the advance of the dials carried from, power escapement mechanisms for carrying into the dials, the advance of the power escapement mechanisms being limited by the respective floating wheel escapement mechanisms, and means for holding the power escapement mechanisms against resistance to the key stroke.
39. In a calculator of the type wherein the dials are advanced on the down strokes of the keys, dials, dial operating mechanism, primary escapement mechanisms for carrying into the dials, auxiliary escapement mechanisms adapted to advance in response to the advance of the dials carried from for predetermining and limiting the advancing movements of the primary escapement mechanisms, key controlled means common to a plurality of escapement mechanisms for timing the advancing movements of the primary escapement mechanisms, and means operative by said key controlled means for holding the primary escapement mechanisms free of resistance to the operation of said key controlled means.
40. In a calculating machine, dials, operating mechanisms for advancing the dials, two escapement mechanisms coöperative with each other, one of which escapement mechanisms comprises a floating stop wheel adapted to advance step-by-step directly responsive to the movement of the dial carried from, a pawl coacting with said stop wheel to limit the extent of advance of the stop wheel and then predetermine and limit the extent of advance of the other escapement mechanism, and the latter escapement mechanism comprising a spring-pressed follow wheel adapted to follow step-by-step the movement of said floating stop wheel,

and mechanism for transferring movement from said follow wheel to its corresponding dial.

41. In a calculating machine, dials, actuating mechanisms for turning the dials, two coöperative escapement mechanisms, one of which comprises a non-driving stop wheel directly responsive to the movement of the dial carried from and a pair of pawls to alternately coöperate with said stop wheel to cause the same to advance one step before a carry movement can be imparted to the corresponding dial, and the other comprising a follow wheel for driving the dial to be carried into and which is held to a one step movement by means of the advanced non-driving stop wheel, and mechanism for holding the follow wheel until the said non-driving stop wheel has reached its advanced position.

42. In a calculating machine, keys, dials, mechanisms actuated by the keys for turning the dials, primary escapement wheels adapted to move step by step regularly to correspond with the zero position of the dials carried from, secondary escapement wheels adapted to move step by step to follow the said primary wheels and which movements synchronize with the upstroke of the keys, and mechanism for transmitting a one-step movement from the secondary wheels to the dials to be carried into.

43. The combination of adding wheels, carrying mechanism comprising an auxiliary escapement wheel controlled by a lower denomination wheel and a driving wheel, and a plurality of oscillatory mechanisms adapted for simultaneous co-action on the driving wheels and the numeral wheels to permit them to advance one tenth of a revolution.

44. The combination of adding wheels, carrying mechanism comprising an auxiliary escapement wheel controlled by a lower denomination wheel and a driving wheel, and a plurality of oscillatory mechanisms adapted for simultaneous co-action on the driving wheels and the numeral wheels to permit them to advance one tenth of a revolution, and a connecting bar for compelling simultaneous oscillation of said mechanisms and means for holding the same against premature oscillation.

45. In a calculating machine, dials, actuating mechanism therefor, a plurality of banks of keys for operating said actuating mechanism, carrying mechanism for each dial, means common to all of said carrying mechanism for controlling the same, shafts one for each bank of keys and common to said control mechanism for operating the same, and operating connections between each bank of keys and its respective shaft.

46. In a calculating machine, dials, oper-

ating mechanism, and a carry mechanism for each dial comprising a stop member adapted to rotate in but one direction and rotated one step during the actuation of 5 the dial of lower order, and an element to operate one step as predetermined by said stop member to effect the carry and normally held against rotation by said member, and means acting independently of 10 said stop member for restraining the movement of said element during rotation of the dials by the operating mechanism.

47. In a calculating machine, the combination with dials, keys, dial operating mechanism operated by the keys, carry mechanisms, and means operated by said keys and common to a plurality of said carry mechanisms for controlling the carry mechanisms, the latter being adapted to exert a load on 15 20 said means which is constructed to hold the load for the purpose of taking it off of the keys.

48. In a calculating machine, the combination with dials, keys, operating mechanism operated by the keys, carry mechanisms, and means including a gear and crank pin operated by said keys for controlling the carry mechanisms, the latter being adapted to exert a load on said means 30 which load is held by the gear and the crank pin to take it off of the keys.

49. In a calculating machine, the combination with dials, keys, operating mechanism operated by the keys, carry mechanisms, a pull bar controlled by the keys and common to a plurality of said carry mechanisms for restraining the operation of said carry mechanism which exerts a load on the bar, and operating connections intermediate 35 40 said bar and keys constructed to take the load off of said keys.

50. In a calculating machine, dials, keys, operating mechanism operated by the keys, carry mechanism, a pull bar, detents operated by said bar and coöperating with said carrying mechanisms which exert a load on the bar through the said detents, and operating connections between said keys and bar constructed to take said load off the keys.

51. In a calculating machine, dials, keys, dial operating mechanism operated by the keys, carry mechanism, means coöperating with said carry mechanisms which are adapted to exert a load on said means, connections intermediate said means and keys operated by said keys in advance of the operating mechanism and constructed to take said load off the keys.

52. In a calculating machine, dials, keys, 60 dial operating mechanism operated by the keys, carry mechanisms, a pull bar common to

said carry mechanisms which are controlled by said bar and exert a load thereon, connections intermediate said bar and keys operated by said keys in advance of the operating mechanism and constructed to take the load off of the keys. 65

53. In a calculating machine, dials, keys, dial operating mechanism for the dials operated by the keys on the down stroke of the latter, carry mechanisms, means coöperating with said carry mechanisms which are adapted to exert a force on said means, connections intermediate said means and keys operated by the keys on their down stroke 70 75 and in advance of the operating mechanism and constructed to take said load off the keys.

54. In a calculating machine, dials, keys, mechanism operated by the keys for operating said dials, carry mechanisms, means coöperating with said carry mechanisms which exert a load on said means, connections including a gear and crank pin intermediate said means and keys operated by 80 said keys in advance of the operating mechanism, the gear and crank pin being adapted to take the load off the keys while the latter is operating said operating mechanism. 85

55. In a calculating machine, dials, an actuator for each dial, a bank of operating keys for each actuator, a shaft carrying each actuator, carry mechanism, detent means therefor, a shaft for each bank of keys for operating the detent means, and connections intermediate the keys of each bank and the appropriate shaft whereby the shaft for operating the detent means is operated on the down stroke of the keys before the actuating shaft is operated on the down stroke of the keys. 90 95 100

56. In a calculating machine, dials, actuating mechanism for each dial, carry mechanism for each dial, detent means for said carry mechanisms, operating means for the detent means, a bank of keys for operating each actuating mechanism and said operating means upon the down stroke of the keys so that the operating means is operated in advance of the actuating mechanism, and an interlock between said actuating mechanism and operating means for locking the actuating mechanism against operation until the keys have operated the operating means. 105 110 115

In testimony whereof I affix my signature in the presence of two witnesses.
